RETAINING DEVICE

Filed Oct. 25, 1926

FIG. 1

FIG. 2

FIG. 3

FIG. 4

Inventor

Donald L. Townsend

By his Attorney

UNITED STATES PATENT OFFICE

DONALD L. TOWNSEND, OF ROCHESTER, NEW YORK, ASSIGNOR TO THE SYMINGTON COMPANY, OF NEW YORK, N. Y., A CORPORATION OF MARYLAND

RETAINING DEVICE

Application filed October 25, 1926. Serial No. 144,093.

- This invention relates to retaining devices and, more especially, to such devices adapted for connection with draft keys to prevent undesired removal thereof.
- 5 The principal object of my invention, generally considered, is the provision of an improved key retainer adapted for application to one or both ends of draft keys for preventing undesired removal or loss thereof.
- 10 An object of my invention is the provision of a draft key retainer comprising a looped member fitting over or encircling an end of an associated draft key, the upper and lower portions of said retainer being provided with 15 apertures registering with a corresponding aperture in the associated key for receiving a connecting pin, said looped member being provided with means thereon for holding said pin in the desired position.
- 20 Another object of my invention is the provision of a retainer adapted for being economically manufactured by casting, if desired, and formed of such a size as to encircle or fit around an end of a draft rigging key, said 25 retainer preferably being formed angular or U shape in cross section and provided at its lower portion with a pin receiving pocket and at its upper portion with a registering pin receiving aperture, said retainer being positioned on an end of an associated key so that 30 the pocket and aperture therein register with a corresponding perforation in the key, said retainer being then retained in place on the key by inserting a preferably headless pin 35 through the aperture in the retainer and key into the pocket in the retainer, said pin being afterwards prevented from loss or undesired removal by inserting cotter means or the like through upward extensions on the retainer 40 above the upper end of the pin.
- A further object of my invention is the provision of a retainer adapted to encircle the end of an associated draft key and be connected thereto by means of a single pin or the like, 45 whereby angling of said retainer with respect to the key is permitted, said retainer being preferably formed convex on its inner surface adjacent the edges of the key whereby angling between key and retainer is facilitated, the connecting means between the re-
- tainer and key being received at its lower end in a pocket in the retainer, which pocket is preferably formed in a lower wall thereof with a relatively small aperture for receiving a tool adapted to remove said pin when desired. 55
- Other objects and advantages of the invention relating to the particular arrangement and combination of the various parts will become apparent as the description proceeds. 60
- Referring to the drawings illustrating my invention, the scope whereof is defined by the appended claims: 65
- Figure 1 is a side elevation of draft rigging and a portion of a car underframe to which the same is applied, particularly showing draft rigging keys with retaining devices thereon embodying the principles of my invention. 70
- Figure 2 is a plan showing fragmentary portions of a draft key with a retaining device embodying my invention applied thereon, a portion of an associated cheek plate being diagrammatically illustrated. 75
- Figure 3 is a transverse sectional view on the line 3--3 of Figure 2 looking in the direction of the arrows. 80
- Figure 4 is a side elevational view of the device shown in Figure 2, the associated cheek plate being shown fragmentarily in section. 85
- Although my invention is adapted for use with draft keys or the like, generally, and for other purposes, and may be used with various kinds of draft rigging, I have, for purposes of illustration, shown in Figure 1 my invention employed with draft rigging of the Farlow two-key type. In said figure, a fragmentary portion of a car underframe is illustrated, draft or center sills 1 being shown with cheek plates 2 applied on the outer sides of the webs 3 thereof in accordance with usual practice. Said cheek plates 2 may be connected to the sills by rivets or the like 4 and are preferably formed with flange portions 5 defining slots 6 and 7 therethrough registering with corresponding slotted portions in the webs 3 of the sills 1. Through the slots 6 and 7 extend draft keys 8 and 9, respectively, and said keys serve for connecting and supporting an associated coupler 10, horizontal yoke 100

11 and front follower 12. Cooperating with the front follower 12 and embraced between the arms of the yoke 11, the cushioning mechanism 13 is illustrated diagrammatically by 5 dot and dash lines.

5 The keys 8 and 9 may each comprise, if desired, a pointed or tapered end 14 and a head 15 on the opposite end thereof. Alternatively, said keys or one of them may be pointed 10 or tapered at each end, if desired. The pointed or headless end or ends 14 of the key 8 or 9, or both, is formed with a perforation or aperture 16 therethrough preferably positioned at the usual distance from the end of 15 the key for application of a key retainer. A preferred embodiment of my improved form of key retainer comprises a member 17 preferably formed as an elongated loop adapted to fit over or encircle the end of the associated 20 key as illustrated in the drawings. Said looped member 17 may conveniently be formed by casting although I do not wish to be limited to such construction. It is desirably formed angular or U shape in cross section, that is, a web portion 18 encircles the key and, in the present embodiment, has a pair of flanges 19 extending outwardly therefrom to provide ample bearing surface for contact 25 with the associated sill or cheek plate thereon.

30 The lower portion or section of the looped member 17 is preferably extended downwardly as indicated at 20 to provide a pocket 21 for receiving the lower end of a connecting member or pin 22. Said pocket is preferably partially closed by the lower wall 23 of the extension 20, forming a supporting step for the pin 22, said wall 23, however, being preferably provided with a relatively small aperture 24 for receiving a piece of 35 wire or tool for pushing the pin 22 upwardly when it is desired to remove the same. The upper portion of the loop 17 is likewise provided with an extension 25 in the form of a boss or circular flange bordering an aperture 26 registering with the pocket 21. The extension or collar 25 is preferably formed with registering apertures 27 adapted to receive cotter means such as a piece of wire or the like 28 inserted and bent, as indicated in 40 Figure 3, to maintain the same in place above the top of the headless pin 22 to prevent undesired loss or removal thereof.

45 It will be apparent that, after the retaining loop 27 has been applied over the end 55 of the key 8 or 9, the headless pin 22 inserted through the registering apertures 26 and 16 and into the pocket 21, the cotter means 28 will then be positioned above the top of the pin 22 which will thereby be retained in position and prevented from loss 60 or undesired removal. When so assembled, a limited amount of angling between the retainer and key is permitted, said angling being facilitated and mutilation of the key 65 being minimized by forming the inner sur-

face of the loop adjacent the edges of the key convex as indicated at 29. It will be apparent that the pin 22, not only is easily inserted in place but may be readily removed by the provision of the aperture 24 through which a nail, a piece of wire or other tool may be inserted to push the key to a height where it may be manually grasped and removed after first straightening one end of the locking means 28 and removing the same. 70

75 Having now described my invention, I claim:

1. A retainer adapted for use with draft keys comprising a looped member fitting over an end of a key, said looped member being formed substantially U shape in cross section for increasing the rigidity thereof and provided with a pocket in the lower section and an aperture in the upper section of 80 said member for receiving a pin to connect said member with the draft key, a headless pin insertable through said aperture and held at its lower end in said pocket, said aperture being bounded by an upstanding collar and means extending through perforations in said collar and above said pin for preventing loss thereof. 85

90 2. A retainer adapted for use with draft keys comprising a continuous loop fitting over an end of a key, said loop being angular in cross section throughout for increasing the rigidity thereof and formed with a pocket in the lower portion and an aperture in the upper portion of said loop, a headless pin inserted through said aperture, a corresponding aperture in an associated draft key and held at its lower end in 95 said pocket, said pocket being formed with a relatively small opening in its lower wall for receiving a tool to force the pin out of said pocket when it is desired to disconnect the retainer from the key, and an upstanding apertured collar framing the aperture in the upper portion of the loop for receiving pin retaining means. 100

105 3. A retainer adapted for use with draft keys comprising a member formed as a continuous loop normally fitting over an end of an associated draft key, said member being formed substantially U shape in cross section for increasing the strength thereof and provided with a pocket in its lower section and an aperture in its upper section for receiving a connecting member, a headless pin inserted through said aperture and held at its lower end in said pocket, said aperture being bounded by an upstanding flange and means extending through perforations in said flange above said pin for preventing loss thereof, the lower wall of said pocket 110 being formed with a relatively small aperture for receiving a tool adapted to remove said pin when it is desired to disconnect the retainer from the key. 120

125 4. A retainer adapted for use with draft

keys comprising a looped member, capable of fitting over an end of a key, having portions extending respectively above and below said key provided with apertures adapted to register with a corresponding aperture near the end of said key, a single pin adapted to extend through all of said apertures to hold said retainer in place on the key, the inner surface of said retainer adjacent the edges of the key being convexly curved to permit a greater degree of angling with respect to said key, and means for holding said pin in place with respect to said retainer.

5. A retainer adapted for use with draft keys comprising a cast member formed as an elongated continuous loop fitting over an end of a key, said loop being formed substantially U shape in cross section for increasing the rigidity thereof, the lower section of said loop being formed with a pocket and the upper section provided with an aperture registering with said pocket, a headless pin insertable through said aperture and a corresponding aperture in an associated key, and held with its lower end in said pocket, said aperture being surrounded at its upper end by an upstanding flange provided with registering perforations, and locking means insertable through said perforations and above 25 said pin for preventing loss thereof.

6. In railway draft rigging, in combination with draft sills, a key extending through slots in said sills for operatively connecting parts of the draft rigging and means for preventing undesired removal of said key, said means comprising a looped member fitting over an end of said key, those portions of said member above and below said key being provided with registering apertures to cooperate 35 with a corresponding aperture near an end of said key, the upper aperture being framed by an upstanding annular collar on said member, a pin for holding said retainer in place on the key and allowing angling of said retainer with respect to said key upon movement of the key in the draft sill slots, and means extending through said collar for preventing loss of said pin.

7. A retainer adapted for use with draft keys comprising a member formed as a loop normally fitting over an end of an associated draft key, said member being generally channel-shaped in cross-section for increasing the strength thereof and provided with a pocket 50 in the lower element of said loop, an aperture in the upper element thereof for receiving a connecting device, a pin substantially uniform in section throughout inserted through said aperture with its lower end received in 55 said pocket, said aperture having an upstanding flange adjacent thereof, and means extending therethrough above said pin for preventing loss thereof.

In testimony whereof I affix my signature.
DONALD L. TOWNSEND.
